UNITED STATES PATENT OFFICE.

EZRA C. FITCH, OF NEWTON, MASSACHUSETTS.

DESIGN FOR A WATCH-BRIDGE.

SPECIFICATION forming part of Design No. 21,423, dated March 22, 1892.

Application filed January 9, 1892. Serial No. 417,577. Term of patent 14 years.

To all whom it may concern:

Be it known that I, EZRA C. FITCH, of Newton, in the county of Middlesex and State of Massachusetts, have invented a certain new and useful Design for Watch-Regulators, of which the following is a specification.

The leading feature of my design consists in a continuous ring or annular plate placed upon or recessed into the balance-bridge of a watch-movement and having radiating lines marked upon a portion of its surface, said ring or annular plate giving a symmetrical and ornamental effect to the balance-bridge.

The accompanying drawing, forming part of this specification, is a perspective view representing my design.

a represents the balance bridge or cock, which is of the usual form and is composed of the base portion 2 and a raised portion 3, the portion 3 having a shoulder 4 at its inner end where it joins the base 2.

d represents the ring or annular plate, which constitutes the leading feature of my design. Said plate is located near the shoulder 4 and imparts a symmetrical and ornamental appearance to the bridge. The exposed surface of the ring *d* may be diversified by radial marks or gradations *d'*.

I claim—

The design for the balance-bridge of a watch-movement, substantially as herein shown and described.

In testimony whereof I have signed my name to this specification, in the presence of two subscribing witnesses, this 2d day of January, A. D. 1892.

EZRA C. FITCH.
